UNITED STATES PATENT OFFICE.

HANS PASSIG, OF LAKE BENTON, MINNESOTA.

GAME APPARATUS.

1,167,655.

Specification of Letters Patent. Patented Jan. 11, 1916.

Application filed April 1, 1915. Serial No. 18,570.

To all whom it may concern:

Be it known that I, HANS PASSIG, a citizen of the United States, residing at Lake Benton, in the county of Lincoln, State of Minnesota, have invented certain new and useful Improvements in Game Apparatus; and I do hereby declare the following to be a full, clear, and exact description of the invention, such as will enable others skilled in the art to which it appertains to make and use the same.

This invention relates to new and useful improvements in game apparatus, particularly of that general type including a ball and certain receiving devices therefor.

The object of the present invention resides in the provision of such a game apparatus which is actuated largely by chance and in which the operation is partially obscured to impart an added element of interest.

A further object of the invention resides in the provision of such a device wherein the scores designated are so arranged that they may be variously added and subtracted to secure a final score thus forming a game which is more interesting and at the same time highly instructive.

With the above and other objects in view, the invention resides more particularly in the novel combination, formation and arrangement of parts more fully hereinafter described and pointed out in the appended claims.

Reference is had to the accompanying drawings wherein similar characters of reference designate corresponding parts throughout the several views, and in which:—

Figure 1 is a side elevation of the improved game apparatus. Fig. 2 is a central vertical sectional view therethrough taken on the line 2—2 of Fig. 1. Fig. 3 is a transverse sectional view on the line 3—3 of Fig. 2, showing one of the floor plans. Fig. 4 is a perspective view of one of the upper floor chutes.

This improved game comprises a casing into which a ball is dropped and passed downwardly therethrough and out at the bottom, actuating during its course through the casing certain indicating means.

Referring now more particularly to the accompanying drawings, there is shown the rectangular casing including the sides 5 and top 6, said structure resting on a base 7 which is provided at its periphery with an up-

standing flange 8 to retain the ball as it is ejected from the casing. This casing is designed to generally represent a house and has disposed therein upper, lower and middle partitions 9, 10 and 11 respectively corresponding to floors. Formed in the sides 5 between the floors and between the bottom floor and the base are series of vertically elongated openings 12 and 13, the openings 13 being large enough to permit the ball or marble which is used in the device to pass therethrough, while the other openings are smaller in width than the marble. Each of the floor portions is concave and is provided with a plurality of openings 14, one of said openings being disposed at the lower portion of the floor to insure the marble rolling through the floor should it miss the other openings. Secured to the floors beneath these openings are a plurality of chutes 15 which extend diagonally downward to the openings 12. The bottom portion of the chutes are cut away as at 16 adjacent the openings to permit the ball to drop on to the next floor. Similar chutes 15' lead from the bottom floor to the openings 13, these chutes not being cut away so that the ball will be ejected from the openings 13.

The top 6 of the casing is provided with a plurality of openings 17 through any of which the ball may be dropped on to the upper floor 9. Thus the ball is dropped in the casing and passes downwardly therethrough and outwardly through one of the openings 13, the ball in its passage coming adjacent certain of the openings 12. To provide a means for registering which of these openings the ball passes, indicator plates 18 are pivoted in said openings and are adapted to swing to lie with their lower portions disposed under the cut away portions 16 of the chutes so that when the ball comes through a chute it will strike one of these plates and move it to a vertical position.

To indicate which of the openings 13 the ball passes out of, indicators 19 are pivoted in the lower portions of the openings and are adapted to be disposed normally in the vertical plane, the ball striking them and swinging them outwardly during its passage through the opening.

In playing the game, each of the indicator plates is provided with a number. The indicator plates are set in position to be actuated by the ball and the ball is dropped

into one of the openings 17. The score is determined in a general manner by considering the total sum of the numbers on the indicators which are struck by the ball.

5 The game may be played in any one of a number of ways, as for instance, if four are playing each one may take a certain side of the casing and count toward his score the numbers carried by the indicators which are 10 struck by the ball on his side, the numbers of the respective openings 17 to which the ball is dropped also being added.

To facilitate a child's proficiency to add and subtract, the score may be determined 15 by adding the numbers of the respective opening 12, the upper indicator 18 and the indicator 19 and subtracting the number of the lower indicator 18.

From the foregoing it is observed that 20 a simple game has been provided which possesses an element of much interest in that the operation of the ball is obscured.

What is claimed, is:—

1. A game apparatus comprising a casing, 25 a plurality of transverse partitions therein each provided with openings, chutes extending from said openings toward the casing for conveying an object from one partition to another, and indicators carried by 30 the casing adjacent the chutes.

2. A game apparatus comprising a casing, a plurality of transverse apertured parti-

tions therein, the casing being provided with openings, indicators pivoted in the openings, and chutes 35 extending from each partition to convey an object from one partition to another to the openings below.

3. A game apparatus comprising a casing, a plurality of transverse apertured partitions therein, the casing being provided with 40 series of openings below said partitions, the lowermost of said openings being enlarged, and chutes extending from each partition to the next lower partition to convey an object 45 to the openings below.

4. A game apparatus comprising a casing, transverse partitions mounted therein and having openings, said casing having openings in its sides, indicators pivotally mounted 50 in the openings, chutes leading from the openings of the partitions to the openings of the sides for conveying an object from one partition to the next lower partition, said object being capable of actuating the indicators when passing from the lower ends of the chutes.

In testimony whereof, I affix my signature, in the presence of two witnesses.

HANS PASSIG.
